Calvin Timmons of the City of New York No

Date of Patent Aug 5 1831

I certify to whom these presents shall come: That I, I. C. Timmons of the City & County of New York, have invented a new and useful improvement in the mode of applying the sap or juice of trees to the bark, and that the following is a full and exact description of the construction and operation of said improvement in the

These pieces are mounted by me in a central part or hub from one to two feet in diameter, made of planed or of one solid piece of wood cut from off a log, & should be iron bound for it may be made of Cast iron; its apex perpendicular & kept in its position by a centre axle or pivot on which it turns, which communicates with a solid fixture below the hub, mortises are made in this central part or hub to receive the ends of the arms No. 44. 73. 93. 13. 73. 93. 73. which are usually from six to eight in number from 10 to 15 feet in length; on the edge of the ends of which turns the hub is set a bent tail that it may be fastened with a key which may be drawn in and taken out at pleasure, or they may be fastened any other convenient way. A notch is cut horizontally in the outer end of each of the arms usually from 45 to 50 degrees & so inclined that the end of the arms shall point downwards

8/2/88

wooden studs or braces between each of the arms
to keep them at equal distances apart, a chain or
rope may be substituted in their stead, & braces
should be placed from the lower part of the
hut to the under side of the arms when the
arms are as long & heavy as to require being sup-
-ported. If a wheel & cylinder placed full with
out the arms which the outer ends of the arms
desire made from one solid log and placed
with its axis horizontal and suspended
in its position by four arms resting in a proper
spherical frame, this wheel & cylinder may
be made separately of planks & boards
placed on the same shaft at such distance
apart & made such size as may best suit
the purpose intended. To. a rope, the
ends of which are fastened to each other
by a iron hook eye that it may be short
ened or lengthened, as occasion may re-
-quire by unhooking & twisting or stretching.
This rope is placed around in the holes in
the outer ends of the arms & passed once around
the wheel & cylinder of this rope a chain may
be substituted. In a movable wheel or pulley
so placed that it may press uniformly against
the rope by means of a weight with which
communicating by a rope passing over a pul-
ley, or cylinder & a weight being attached
and so a spring may be substituted in order to stop
the rope from getting tight should it stretch, or shrink
to a frictionless gauge wheel placed in a pro-
per position to guide the arms the wheel to be

into the wheel D smoothly. When the above described apparatus or horse power is taken part in motion one or more horses are placed between & near the outer ends of the arms just inside the rope & hitched to the arms immediately behind them by means of which they are made to walk in circular track, and causing the arms to revolve. The rope being drawn tight by means of the movable wheel E, & weight will be prevented from slipping in the notches in the ends of the arms & in the groove of the wheel D. Consequently rotary motion will be communicated to the said wheel of drum, the number of revolutions of the wheel D will be in proportion to the diameter is with that of the circle described by the ends of the revolving arms of deduction being made for the straight parts of the rope between each of the arms; in many instances the above mentioned wheel and drum D. may be dispensed with by passing the rope E around a wheel on the machine which is to be put in motion, & carrying the movable wheel E & weight in any convenient place. Also the wheel D. may be placed on a shaft whose axis is perpendicular as in driving a Horse Power mill in which case the wheel D may be placed on the mill stone spindle. What I claim as new and as my own invention or discovery in the above described horse power or machine for the use of which I seek an exclusive privilege in the construction & arrangement of the several

Particulars of classification of the application to the
prosecuting of machinery by animal power
